UNITED STATES PATENT OFFICE

90,480

DESIGN FOR A FABRIC

Joseph Erkes, Philadelphia, Pa., assignor to
Collins & Aikman Corporation, Philadelphia,
Pa., a Corporation of Delaware

Application May 8, 1933. Serial No. 48,038

Term of patent 14 years

To all whom it may concern:

Be it known that I, JOSEPH ERKES, a citizen of the United States, residing at 1104 Kenwyn Street, Frankford, Philadelphia, in the county of Philadelphia and State of Pennsylvania, have invented a new, original, and ornamental Design for Fabrics, of which the following is a specification, reference being had to the accompanying drawing forming part thereof.

In the drawing, Fig. 1 is a top plan view, Fig. 2 is an edge view and Fig. 3 is a magnified fragmentary view of a fabric section embodying my new design in which groups of relatively long loops projecting upward from the base are spaced by groups of relatively short loops or tufts project-

ing upward from the base, each pair of groups of short loops or tufts having between them a recess or groove.

The actual size of the fabric design varies with the count of the yarns used in its manufacture. The size shown in Fig. 1 of the drawing filed is one actual size of the fabric design, but the reduction of either Fig. 1 or Fig. 3 of the drawing filed to patent size will show approximate actual sizes of the fabric design made with yarns of different count or diameter.

I claim:

The ornamental design for a fabric as shown and described.

JOSEPH ERKES,
